CLAIM

The ornamental design for a perfume bottle, as shown and described.

DESCRIPTION

1.-2. Perfume bottle

Figure 1.1 is a front elevation view of the perfume bottle; Figure 1.2 is a rear elevation view of the perfume bottle of Figure 1.1;

Figure 1.3 is a left side elevation view of the perfume bottle of Figure 1.1, the right side being a mirror image thereof; Figure 1.4 is a bottom plan view of the perfume bottle of Figure 1.1;

Figure 1.5 is a rear right perspective view of the perfume bottle of Figure 1.1;

Figure 1.6 is a top plan view of the perfume bottle of Figure 1.1; and

Figure 1.7 is a front left perspective view of the perfume bottle of Figure 1.1.

The broken lines in Figure 1.1, 1.2, 1.3, 1.5, and 1.7 depict portions of the article that form no part of the claimed design.
